UNITED STATES PATENT OFFICE

FREDERICK E. MAYNARD, OF LOS ANGELES, CALIFORNIA

ONE-PIECE RAT GUARD

Application filed August 18, 1925. Serial No. 50,939.

This invention relates to rat guards for ships' hawsers, to prevent disease bearing rodents from passing to or from dock or ship.

A guard of such size as to comply with 5 United States regulations, to be durable and rigid must be of stiff metal, unless well braced.

An object of my present invention is to provide for use of stiff metal and eliminate braces, and at the same time provide a guard 10 at low cost, which is an important item, considering that rat guards are special equipment bought and used only under compulsion by ship people.

An object is to provide a knock-down guard. 15 An object of this invention is to obtain utmost simplicity, fewest possible pieces, and minimum cost of manufacture.

The invention consists of the improved 20 guard and a method of making it.

Figure 1 is a perspective of the guard on a line.

Figure 2 is a plan of the plate blank.

Figure 3 is a plan of a portion of the slit 25 plate.

Figure 4 is a cross-section of a finished plate.

Figure 5 is a plan of a portion of the slit shutter blank.

Figure 6 is an edge view of Figure 5.

Figure 7 is a plan of a sleeve blank.

Figure 8 is a front elevation of an open 30 guard.

The cost of cutting a 36 inch disc from a piece of #20 or #22 iron is considerable and 35 an object is to eliminate this cost.

The guard includes an octagonal plate 3 cut from a square blank 2. This I radially slit at 4, and also at 5 to form tongues 6 by bending up the points formed after the slits 5 are made. The tongues are perforated at 7 for bolts. The metal along the slit 4, to the center of the disc, is folded back flat at 8 on the disc. The sharp points of the horns 5 may be cut off as they might stick in or cut a fiber 45 or hemp rope.

To hold the plate 3 perpendicular to a hawser a split sleeve is bolted to it to project from one side. This sleeve is made of duplicate sheet members 9. One end is slotted to 50 form fingers 10 and along the opposite end

are holes 11 so spaced that when the member is bent to half-round form, the holes 11 will register with the holes 7 of the up-bent tongues 6 of the plate 3, so that a sleeve member can be attached by bolts 12 to the plate 3. 55

A pair of the sleeve members 9 is connected along one edge by common "butt hinges" 13 which are preferably riveted on.

When the lips of the slit 4 are folded back there is thus formed a slot 14 for the entrance 60 of any size hawser up to the width of the slot.

To close this slot a shutter is made of a flat blank 15 of sheet metal. This is radially slit at 16 to form tongues 17 at the center of one end; the blank being so long that one end can 65 be folded as a hook 18 over the edge of the plate 3.

One member of the sleeve is riveted or bolted around the tongues 17 of the shutter 15.

In knocked down condition, a large number 70 of the plates 3 can be stacked flat upon each other; the tongues of one nesting in those of the next above. To pack the sleeves these are opened on their hinges 13 and laid tunnel-like, then others are stacked from bottom up; the 75 shutters 15 standing close in a row back to back.

This feature of packing in knocked-down condition is important both for conserving 80 store and ship space, and for permitting a number to be crated in compact condition for transportation.

This method of making the guard has been found to be highly satisfactory because there is not a single curve line to be cut. Every 85 sheet metal piece is straight edge and is cut in with high economy from sheets 108 by 36 inches in size.

Braces are completely eliminated by bending over very narrow (1/4 inch) laps 20 all 90 around the perimeter of the plate 3. This effectively stiffens the whole plate.

What is claimed is:

1. In a rat guard, a member formed of a blank having a slit radial to a center point, 95 and having radial slits from said point to form triangular tongues bendable to stand in an arc.

2. In a rat guard, a member formed of a blank having slits radial from a point in its 100

center to form tongues bendable to stand in an arc.

3. In a rat guard, a slotted plate part and a shutter part to close the slot, the parts having integral fastening tongues, in a circle, when the shutter is closed, and half sleeves overlapped on and secured to respective groups of the tongues on the parts; the half sleeves being hinged together.

4. A knock-down rat guard including a pair of hinged, half-round sleeve members forming a cylinder, a shutter to which one end of one sleeve member is attached, all said parts forming a unit, and a plate having triangular tongues turned out to form a semicircular hole and to which the other member is boltable to complete the guard.

5. A rat guard having a plate adapted to substantially encompass a support and having a radial slot to its rim, a set of tongues, integral with the plate, in a semicircle at the inner end of the slot and bent perpendicular to the plate, a half-sleeve secured on the tongues, and a slot shutter pivotally related to the plate and having a half-sleeve matching the opposite half-sleeve.

6. A rat guard including a plate having a radial slot, with a half-round inner end, a slot shutter pivotally related to the plate and having a half-round recess in its inner end, sets of tongues bent to stand unidirectionally from the plate and the shutter, and half-sleeves secured to the set of lugs on the shutter and the plate to form a rope sleeve.

7. A rat guard including a plate having a radial slot, a semicircle of tongues bent out from the plate around the inner end of the slot, a slot shutter having on its inner end a semicircular set of tongues bent therefrom and forming a half-round recess, and a pair of half-sleeves hinged along one side and connected to respective sets of lugs, whereby to pivotally relate the plate and shutter.

8. A rat guard including a plate having a radial slot, a semicircle of tongues bent out from the plate around the inner end of the slot, a slot shutter having on its inner end a semicircular set of tongues bent therefrom and forming a half-round recess, and a pair of half-sleeves hinged along one side and detachably connected to respective sets of lugs, whereby to pivotally relate the plate and shutter.

9. The steps in the making of a rat guard, which consist of radially slitting its guard members to form, in each, a set of radial tongues, then bending the tongues out perpendicularly to the respective members so as to stand in a semicircle.

10. The steps in the making of a rat guard, which consist of radially slitting its guard members to form, in each, a set of radial tongues, then bending the tongues out perpendicularly to the respective members so as to stand in a semicircle; the tongues being

perforated, for rivets or bolts, at any time before they are bent up.

11. The steps in the making of a rat guard, which consists of radially slitting its guard members to form, in each, a set of radial tongues, then bending the tongues out perpendicularly to the respective members so as to stand in a semicircle, and perforating and shaping sleeve blanks to fit the sets of tongues, and securing them thereto.
